DISPENSER OF EDIBLES OR SIMILAR ARTICLE

Burl T. Wood, Lindsay, Calif., assignor to Lindsay Ripe Olive Company, Lindsay, Calif., a corporation of California

Filed Apr. 20, 1965, Ser. No. 84,880

Term of patent 14 years

(Cl. D44—24)

FIG. 1.

FIG. 3.

FIG. 2.

FIG. 4.

FIGURE 1 is a side elevational view of a dispenser of edibles or similar article showing my new design;

This application is a continuation-in-part of my co-pending application, Serial No. 78,730, filed February 21, 1964, and now abandoned.

I claim:

The ornamental design for a dispenser of edibles or similar article, as shown and described.
